UNITED STATES PATENT OFFICE.

RUDOLPH MUELLER, OF NEW YORK, N. Y.

DESIGN FOR A MIRROR-FRAME.

SPECIFICATION forming part of Design No. 32,733, dated May 29, 1900.

Application filed May 1, 1900. Serial No. 15,141. Term of patent 7 years.

To all whom it may concern:

Be it known that I, RUDOLPH MUELLER, a citizen of the United States, residing at New York, in the county of New York and State of New York, have invented and produced a new and original Design for Mirror-Frames, of which the following is a specification.

The drawing illustrates a mirror-frame embodying my new and original design.

Referring to the drawing, the leading or material feature of my design consists of a frame denoted by the general reference character *a*, the sides *b* whereof are slightly divergently arranged, the top *c* and bottom *d* embodying reverse curves.

Arranged about the frame *a* are a plurality

of fanciful representations *e*, denoting leaves, flags, armorial implements, and implements of warfare, all of the form shown in the drawing.

Having fully described my invention, I claim as new and desire to secure by Letters Patent—

The design for a mirror-frame, substantially as shown and described.

In testimony that I claim the foregoing as my invention I have signed my name, in presence of the subscribing witnesses, this 30th day of April, 1900.

RUDOLPH MUELLER.
